UNITED STATES PATENT OFFICE.

JOHN B. HERGET, OF SEATTLE, WASHINGTON, ASSIGNOR OF ONE-HALF TO PAULINE E. HERGET, OF PORTLAND, OREGON.

DUMP-CAR.

1,249,624.

Specification of Letters Patent.

Patented Dec. 11, 1917.

Application filed May 15, 1916. Serial No. 97,616.

To all whom it may concern:

Be it known that I, JOHN B. HERGET, a citizen of the United States, residing at Seattle, county of King, State of Washington, have invented certain new and useful Improvements in Dump-Cars, of which the following is a specification.

My invention relates to dump cars in general, and particularly to devices whereby the cars may be dumped when coupled in train, and has for its object the providing of means, simple, effective and positive, whereby the cars may be dumped from the locomotive, using the power thereof for that purpose.

I accomplish the above object, and other useful and desirable results, by means of the construction illustrated in the accompanying drawings, which therefore become a part of this application for Letters Patent, like characters of reference indicating like parts throughout the several views, in which;

Figure 1 is a side elevation of a dump car embodying my invention, parts being broken away to illustrate the construction.

Fig. 2 is a plan view of the subject matter of Fig. 1.

Fig. 3 is a sectional elevation upon the line 3—3 of Fig. 1.

Fig. 4 is a side elevation of a train of dump cars being dumped by means of my device operated from the locomotive.

Fig. 5 is a side elevation of a side dump car embodying my invention.

Fig. 6 is a sectional elevation upon the line 6—6 of Fig. 5.

In general my invention consists of a cable passed along the train from the foremost car to the rear car and engaging with suitable sheaves upon each car, whereby, when the brakes are set upon the train and the locomotive uncoupled therefrom and the forward end of said cable attached to the locomotive, the power of the locomotive applied to said cable may be utilized for dumping all the cars in the train.

In applying my invention to a bottom dump car, the body may be constructed of sills 1 connected with suitably spaced cross members 2, and a body 3 superposed upon the sills.

A superstructure is erected upon sills 1 consisting of members 4 seated upon said sills at each end thereof, said members be-

ing in juxtaposition at the upper ends thereof, thereby forming an A frame upon each end of the car, as shown in Figs. 2 and 3, and longitudinally disposed members 5 mounted upon the upper ends of members 4, and adapted to receive there-between the operating members of my device.

To close the bottom of the car I provide plates 6 longitudinally disposed within the car body 3 and lying upon cross members 2, each of said plates covering one half of the body space, and the adjoining edges of said plates being longitudinally disposed upon the center line of the body of said car.

Said plates are pivotally connected by means of eye-straps 7 secured thereto adjacent the adjoining edges thereof, and each engaging with a link of a chain 8, as shown in Figs. 1 and 3.

For the purpose of dumping the car said plates 6 are to be lifted into the position shown in Fig. 3, and for that purpose a sheave 9 is secured to the upper end of the chain 8 by means of a forked strap 10.

To operate said sheave 9 for opening or closing the bottom plates 6, I provide a pair of sheaves 11 rotatably mounted between members 5 immediately above sheave 9, and disposed so as to allow sheave 9 to pass between said sheaves 11, as shown in Figs. 1 and 4.

A cable 12 is disposed longitudinally of the car, substantially between members 5, passing over sheaves 11, downwardly between same, and beneath sheave 9, as shown in Figs. 1 and 4.

When a loaded train is to be dumped the locomotive is uncoupled therefrom and the train brakes set; the rearward end of the cable 12 is tied or otherwise fastened to the rear coupling head or other convenient place, and the forward end of said cable is secured to the draw bar of the locomotive, as shown in Fig. 4.

By moving the locomotive away from the train the cars will be successively dumped, starting with the foremost car.

In the illustrations I have shown the cars constructed of two compartments each, with a transversely disposed diaphragm 13 there-between, this being the construction preferably adapted for large cars.

The preceding description and the illustrations corresponding thereto relate to cars

that dump from the bottom, but my invention may be applied to other types of dump cars, and as an example I have illustrated the same applied to the ordinary side dump 5 tilting body car, as shown in Figs. 5 and 6, wherein sheaves 14, corresponding in function to sheaves 11 previously described, are disposed in pairs upon opposite sides of the central longitudinal sill 15 of the car, 10 being mounted thereon by means of a cross arm 16, as shown in Figs. 5 and 6.

Sheaves 17, corresponding in function to sheave 9 previously described, are pivotally secured beneath the tilting body by means 15 of a forked strap 18 and a bracket 19 secured to said tilting body.

In a car of this construction the system of sheaves 14 and 17 and cable 18, is duplicated, one such system being longitudinally 20 disposed upon each side of the center line of the car, and beneath the car body.

If, when the train is in transit, both of 25 said cables 18 are stretched tightly and secured to the cars respectively at the rear and at the front ends of the train, all the tilting bodies of the cars in the train will thus be locked in place against accidental tilting and dumping in transit.

When it is desired to dump the cars upon 30 one side, the cable 18 upon the opposite side is released, and the cable upon the side toward which it is desired to dump is attached to the locomotive, and thus the dumping operation is accomplished as previously 35 described.

My invention may be made of any size and constructed of any materials deemed 40 convenient and suitable for a device of this character, and while I have illustrated and described a form of construction and arrangement of parts found desirable in materializing my invention, I wish to include in this application for Letters Patent all mechanical equivalents and substitutes that

may fairly be considered to come within the 45 scope and purview of my invention as defined in the appended claims.

Having disclosed my invention so that others skilled in the art may be enabled to construct and use same what I claim as new 50 and desire to secure by Letters Patent is;

1. In a dump car, a floor plate; a pair of sheaves disposed longitudinally of said car adjacent one edge of said floor plate, said sheaves being aligned one with the other; a 55 sheave attached to said floor plate and adapted to move into a position intermediate said first mentioned sheaves and aligned therewith; and a cable secured to one end of said car and passing over one of said first 60 mentioned sheaves, thence around said second mentioned sheave attached to said floor plate, thence over the other of said first mentioned sheaves, and thence to a source of power extraneous to said car. 65

2. In a dump car, a bottomless hopper: transversely disposed beams within said hopper adjacent the bottom thereof; a pair of floor plates loosely disposed upon said floor beams, their adjacent edges being hinged 70 together; a pair of sheaves mounted above said plates and in line with the hinged edges thereof; a sheave attached to the hinged edges of said floor plates immediately below said first mentioned sheaves; and a cable 75 secured to one end of said car and passing over said sheaves to some source of power extraneous to said car.

In witness whereof I claim the forgoing 80 as my own I hereunto affix my signature, in the presence of two subscribing witnesses, at Seattle, county of King, State of Washington, this 18th day of April, 1916.

JOHN B. HERGET.
